DOOR HANDLE GUARD

David Frees, Sun Valley, and Edwin L. Schwartz,
Los Angeles, Calif.

Application February 16, 1953, Serial No. 23,646

Term of patent 7 years

(Cl. D10—8)

Be it known that we, David Frees and Edwin L. Schwartz, both citizens of the United States of America, residing in Sun Valley, county of Los Angeles, State of California, and Los Angeles, County of Los Angeles, State of California, respectively, have invented a new, original, and ornamental Design for a Door Handle Guard, of which the following is a specification, reference being had to the accompanying drawing, forming a part thereof.

Figure 1 is a perspective view of a door handle guard, showing our new design with a door handle shown in dotted outline for illustrative purposes only;

We claim:
The ornamental design for a door handle guard, substantially as shown and described.
